PROCESS FOR TREATING TOBACCO

Max-Bartold Freiherr von Bethmann, Bremen, Germany, assignor to Martin Brinkmann K. G., Bremen, Germany, a firm

Application September 9, 1954, Serial No. 455,641

Claims priority, application Germany September 17, 1953

20 Claims. (Cl. 131—140)

The present invention relates to a process for treating tobacco and more particularly to a process for de-nicotinizing tobacco in such a way as to reduce the nicotine content to an insignificant fraction of the nicotine originally present in the tobacco, while retaining all other ingredients and consequently leaving flavor, taste, and aroma substantially unimpaired.

For many years solutions to the problem of denicotinizing tobacco without impairing its flavor, taste, and aroma have been sought and various methods have been proposed. However, up to now it has not been possible to remove the nicotine from tobacco without at the same time unfavorably affecting its flavor.

It is known to render tobacco or a tobacco extract alkaline in order to free the nicotine which then can be driven off by various methods. This process deleteriously affects the flavor of the tobacco due to chemical reactions occurring when the pH of the tobacco or of tobacco extract is raised above 7 and also because in the process of eliminating the free nicotine, volatile flavoring components are lost.

In order to avoid these disadvantages of the alkaline de-nicotinization methods it has been suggested to extract tobacco with water, alcohol or other solvents. By these treatments, however, not only the nicotine but also the other ingredients, soluble in the chosen solvent, are removed. This of course also deleteriously affects the quality of the so treated tobacco and consequently these methods too have only found limited application.

Combinations of these two methods have also been tried without leading to useful results.

In another approach to this problem it has been suggested to de-nicotinize tobacco by submersion in water for prolonged periods of time, until the nicotine is destroyed by bacterial action. It was found, however, that bacterial action cannot be limited to the destruction of the nicotine alone, but other extractives of the tobacco, such as sugars, pectins and the like, which are important for the flavor of the tobacco, were also affected.

It appears that the known methods for the de-nicotinization of tobacco have achieved the result of eliminating a considerable part of the nicotine originally present in the tobacco, they have completely failed, however, in providing a de-nicotinized tobacco of satisfactory, original tobacco flavor.

It is an object of the present invention to provide a process for the de-nicotinization of tobacco which overcomes the above mentioned disadvantages of existing methods.

It is a further object of the present invention to provide a process according to which de-nicotinized tobacco can be produced which is substantially the equal in flavor of the original tobacco prior to de-nicotinization, and yet has a nicotine content of less than 20% of its original nicotine content.

It is still another object of the present invention to provide a process for the de-nicotinization of tobacco that can be exercised with large commercial quantities, result-

2

ing in a de-nicotinized tobacco of unimpaired flavor, and to do so in an economical and easily controllable process.

Other objects and advantages of the present invention will be apparent from a further reading of the specification and of the appended claims.

With the above objects in view the present invention mainly comprises a process of extracting nicotine from tobacco, comprising the steps of treating tobacco with water so as to extract the water soluble components of the tobacco including the nicotine and form an aqueous extract solution thereof, separating the aqueous extract solution containing the nicotine from the thus extracted tobacco, subjecting the thus separated extract solution to ion exchange with an ion exchanger adapter to remove the nicotine from the extract solution, thereby obtaining a de-nicotinized extract solution, mixing the de-nicotinized extract solution with the extracted tobacco so as to form a water-tobacco mixture including the water soluble components of the original tobacco except for the nicotine, and drying the water-tobacco mixture so as to obtain a de-nicotinized tobacco containing substantially all of the original water soluble components thereof except for the nicotine.

It has been found that tobacco de-nicotinized by the process of the present invention contains practically all extractives and in the same amount present in the untreated tobacco with the exception of the nicotine. Thus treated tobacco therefore completely retains its original desirable flavor.

Best results are obtained with the process of the present invention by executing the water extraction in consecutive steps whereby in each step the weight relationship between the tobacco and the extract solution serving as solvent is adjusted to a predetermined proportion preferably of between 8 and 12 units by weight of solvent to 1 unit by weight of tobacco and most preferably 10 units of water per each unit of tobacco.

After the tobacco has been substantially completely extracted it is then treated with concentrated de-nicotinized extract solution coming from the ion exchanger. This extract solution contains practically all the soluble ingredients previously extracted from the tobacco with the exception of the nicotine. By drying together a mixture of extracted tobacco and de-nicotinized extract solution, and by properly adjusting the concentration of the extract solution and the quantity of extract solution to be dried with reference to the amount of extracted tobacco, it is possible to obtain, if desired, a reconstituted de-nicotinized tobacco containing all extractives, except for the nicotine, in substantially the same proportions in which they were present prior to the treatment of the original tobacco.

It has been found advantageous to mix together extracted tobacco and a de-nicotinized tobacco extract solution containing a percentage of extractives equal to the percentage of extractives that were originally present in the untreated tobacco, except for the nicotine. In such event it is possible to finally dry extracted tobacco mixed with an equal weight of extract solution so that the finally dried tobacco contains the same percentage concentration of extractives, except for nicotine, as the original untreated tobacco. This is advantageous in that it has been found that the drying of tobacco with an equal weight of extract solution permits the best drying without the necessity of using heat to a greater extent than in the customary drying of tobacco and without any possibility of dripping off of the solution which would affect the concentration of extractives in the final dried tobacco. This is most advantageously achieved by recycling the extracting solution through the steps of the tobacco extraction and the ion exchanger until the concentration of extractives in the extracting solution

reaches an equilibrium with the concentration of extractives in the original tobacco.

To the extent that the ion exchanger retains metal ions from the tobacco extract solution and possibly changes the pH of the solution, the original pH and content of metal salts can be restored in the de-nicotinized solution by cycling the solution through a tower filled with for example magnesium carbonate or dolomite. As will be shown below, only part of the de-nicotinized tobacco extract solution leaving the ion exchanger is used for mixing with extracted tobacco in order to reconstitute in the tobacco the previously extracted ingredients except for the nicotine. Another portion, and frequently the larger portion of the de-nicotinized extract solution leaving the ion exchanger, is used as solvent for the extraction of the tobacco and thereafter is pumped again through the ion exchanger.

In order not to unnecessarily overload the ion exchanger and also to reduce the amount of magnesium carbonate used, only that portion of the de-nicotinized tobacco extract solution leaving the ion exchanger which is to be used for mixing with the extracted tobacco, will be cycled through the magnesium carbonate tower.

The preferred pH value to be obtained by cycling of the de-nicotinized tobacco extract solution through the magnesium carbonate tower is within the range of pH 4.0 to 5.5. It is important to note that during the whole process an increase of the pH into the alkaline range, with its harmful consequences, is avoided.

The mixture of extracted tobacco and de-nicotinized, pH-adjusted tobacco extract solution may then be dried by any of the conventional methods, preferably without the use of substantially elevated temperatures and thus without danger of undesirable chemical reactions or loss of volatile ingredients.

In a preferred embodiment of the process of the present invention tobacco is extracted with water in three consecutive steps, using for the extraction of one part by weight of tobacco, ten parts by weight of water and proceeding with the extraction in each step for one hour at room temperature. After completion of each step nine parts of the solution are squeezed out, leaving one part in the tobacco. Upon repeating the extraction step three times, while moving tobacco and water solution in countercurrent direction from step to step, substantially all of the nicotine with the exception of a fraction of 1% is removed from the tobacco.

This countercurrent, step-wise extraction process may advantageously be executed in a cycle, whereby the concentrated extract solution after being used in three consecutive extraction steps is de-nicotinized in the ion exchanger and thereafter re-introduced in the cycle by being used for the final extraction of tobacco which has previously already been extracted in two successive steps. At this final extraction step of the tobacco fresh water is added, together with the de-nicotinized tobacco extract solution coming from the ion exchanger, in the amount required to replace the water which leaves the process with the reconstituted de-nicotinized tobacco and extract mixture.

By following the above procedure, de-nicotinized tobacco of very high quality can be produced, since substantially all ingredients except for the nicotine are retained. Furthermore, only a relatively small amount of water, approximately equal to the weight of the dry tobacco, has to be removed and this drying process can easily be arranged at the conventional tobacco drying temperature and without appreciable loss of volatile ingredients, or heat-induced chemical reactions. In addition, the concentrated extracts obtained by this process show excellent resistance against fermentation and spoilage.

The process of the present invention may also be utilized in the production of de-nicotinized tobacco extracts from tobacco waste and dust. About 30 to 40% water

solubles may be extracted from tobacco waste products and de-nicotinized as outlined above. The resulting de-nicotinized tobacco extract solutions may be used to improve the quality and increase the strength of tobaccos which may or may not have been previously de-nicotinized.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawing, in which:

15 Fig. 1 is a diagrammatic view of an installation for the performance of the process of the present invention; and

Fig. 2 is a schematic illustration of the various manners in which three ion exchangers can be operated in accordance with the present invention.

20 Referring now to the drawing and particularly to Fig. 1, it can be seen that the untreated tobacco enters tank 2 by means of a suitable conventional feeding arrangement 1. In tank 2 the tobacco is extracted with a tobacco extract solution coming from tank 5. After

25 being extracted for about one hour at room temperature, the tobacco is moved by means of conveyor 3 through a set of rollers 4 into tank 5. In one of the processes included within the present invention, the tobacco is treated in tank 2 with 10 times its weight of tobacco extract solution. By being squeezed through the set of rollers 4, a part of the extract solution adhering to the tobacco is forced back into tank 2. The set of rollers 4 may be so adjusted that tobacco containing an amount of extract solution equal to its own dry weight is dumped into tank 5.

30 In tank 5 a second extraction of the tobacco with for instance 10 times its own weight of extract tobacco solution takes place, the tobacco extract solution coming from tank 8. After about an hour of extraction, the tobacco is moved by means of conveyor 6 through a set of rollers 7 into tank 8. Again the set of rollers may be adjusted in such a way that the tobacco reaching tank 8 will contain extract solution in an amount equal to its own dry weight.

35 In tank 8, a third and final extraction of the tobacco takes place. The extract solution used in this extraction enters tank 8 through conduit 18. The amount of extract solution available through conduit 18 will not quite suffice, therefore. Water is added through faucet 11 in an amount sufficient to make up the difference.

40 The tobacco extract solution used for the extraction of fresh tobacco in tank 2, leaves tank 2 through conduit 13 and is pumped by means of pump 14 through filter 15 (for the removal of solid impurities) into ion exchanger 16. In ion exchanger 16 the nicotine and some of the metal ions are removed from the extract solution which is then pushed through conduit 17 into conduits 18 and 20. The part of the de-nicotinized extract solution permitted to flow through conduit 18 enters tank 8 and is there used 45 for the final extraction of the tobacco as outlined above.

45 The tobacco leaving tank 8 by means of conveyor 9 is squeezed through a set of rollers 10 so as to contain an amount of extract solution equal to its own weight, and falls into tank 19. The tobacco received in tank 19 is 50 already sufficiently freed of nicotine. Since not only the nicotine but also other soluble ingredients have been extracted, it is now necessary to reconstitute these other soluble ingredients in order to restore the tobacco to its original flavor.

55 For this purpose de-nicotinized tobacco extract solution coming from ion exchanger 16 by way of conduits 17 and 20 is added. This extract solution contains all soluble ingredients of the original tobacco except for the nicotine and the metal ions which were retained in the ion exchanger. In order to restore the metal ions to the

de-nicotinized tobacco extract solution in tank 19, the solution is cycled through conduit 21, pump 22, and the magnesium carbonate containing column or tower 23, and finally through conduit 24 back into tank 19. The speed of flow is so arranged as to permit the solution, while passing through the magnesium carbonate tower 23, to pick up the metal salts in a percentage amount equal to the percentage of metal salts contained in the original tobacco.

In the execution of the process here discussed, it is desirable to have the concentration of all tobacco solubles, except nicotine, in the extract solution in tank 19 reach a percentage equal to the percentage of these solubles in the original untreated tobacco which has been extracted therefrom.

The extracted tobacco coming from the set of rollers 10 is mixed in tank 19 with the above described nicotine-free tobacco extract solution and removed from tank 19 by way of conveyor 25 and rolls 26. Rolls 26 are so adjusted as to squeeze out of the tobacco all extract solution in excess of an amount equal to the dry weight of the tobacco.

The moist tobacco coming from set of rollers 26 is then air or otherwise dried by known methods so as to prevent volatilization of flavoring components. The dried tobacco will then contain all soluble ingredients except nicotine in the same proportions in which they were present in the original untreated tobacco.

The cation exchanger 16 may be arranged as an hydrogen ion exchanger or as a metal ion exchanger, preferably a potassium ion exchanger.

The advantage of the potassium ion exchanger lies in the fact the pH value of the de-nicotinized extract solution remains practically unchanged. However, the capacity of the potassium ion exchanger is somewhat smaller, furthermore, it is necessary to regenerate the exchanger first with hydrochloric acid and then to transform it into a potassium exchanger with the help of potassium chloride solution. This is necessary because a cation exchanger after being saturated with nicotine can only be quantitatively regenerated by way of the hydrogen ion exchange arrangement.

The extract solutions leaving a cation exchanger in its hydrogen ion form are, especially at the beginning of the operation, rather far on the acid side. The advantage of this is that the solutions remain stable at a pH below 3 and it is then not necessary to arrange for additional precautions in order to prevent fermentation during the treatment of the extracts. Working in this way, however, practically all metal salt ions are taken out of the solution. Consequent disadvantages can be eliminated by treating the extracts with suitable salts after they have left the exchanger column. Preferably the original pH value of between 4.0 and 5.5 can be readjusted by piping the extract over magnesium carbonate or dolomite.

In order to prevent an unnecessary load on the exchanger columns and in order not to use up too large quantities of salts like magnesium carbonate, it is desirable to adjust the pH of only the part of the de-nicotinized extract solution which will remain in the treated tobacco and not to adjust the pH of the part of the extract solution which will be used in countercurrent for the de-nicotinization of additional quantities of tobacco.

The execution of the tobacco extraction process may be so controlled that the relation between tobacco and water throughout the whole system is maintained as 1:10, whereby the tobacco remains for about one hour in the individual extraction steps and contains upon leaving the system, with the exception of the nicotine, all the extractives that were removed in the preceding operations. The sets of rolls are then preferably so adjusted that 1% of the solution from the preceding process step are kept back.

Such treated tobacco contains practically 100% of its original extractives, exclusive of nicotine and similar

amino-compounds. If desired, it is also possible to add to the extract solution in tank 19 other ingredients which are advantageously and customarily added to the tobacco, such as cane sugar, invert sugar or glucose, sorbitol, glycerol, glycols, aromatic fruit extracts, also glow promoting substances such as saltpeter, and the like.

The tobacco coming from the last set of rolls may be dried in conventional ways to the usual moisture content required for the cutting of the tobacco. It has proven especially advantageous to remove the surplus water under reduced pressure. It is also possible to accomplish the final drying to the usual moisture content in known ways by roasting the cut tobacco.

It is advantageous to use in the execution of the process of the present invention several, for instance 3, connected ion exchanger columns of suitable size in series. Hereby the first column is first charged to capacity, while it is the purpose of the second and third columns to exchange the quantities of nicotine which after some time start to pass through column 1. Later on, one proceeds in such a way that as soon as nicotine passes through the second column, the third column is connected and the first column disconnected for regeneration. When nicotine starts to pass through the second column, the regenerated first column is added to the series and the second column is cut off for regeneration, and so on.

As schematically shown in Fig. 2, the three ion exchanger columns 1, 2 and 3 can be operated in various ways so that always two columns operate in sequence while one column is regenerated.

The three columns can be operated according to three different schedules.

According to schedule 1, column 1 and 2 operate in sequence and column 3 is regenerated.

According to schedule 2, columns 2 and 3 operate in sequence and column 1 is regenerated.

According to schedule 3, columns 3 and 1 operate in sequence and column 2 is regenerated.

When operating according to schedule 1, valves 1, 2, 3, 4, 5 and 6 are open and valves 7, 8, 9, 10, 11, 12, 13 and 14 are closed. The extract solution which is to be de-nicotinized enters through valve 1 and leaves the ion exchange system through conduit 30. During operation of the apparatus, small quantities of the liquid may be drawn off at valve 15 for testing whether nicotine is present in the liquid leaving the ion exchangers, thus indicating that column 1 has been saturated and should be replaced by column 3. A suitable precipitation reaction, for instance with silicotungstic acid may be employed for this test. When regenerating column 3, valves 19, 24 and 25 are open, and valves 20, 21, 23, 26, 27 and 28 are closed. The regenerating solution enters through valve 19 and is released after completion of the regeneration process through valve 28. Prior to releasing the regeneration solution it is necessary to check that the regeneration solution leaving through conduit 29 is substantially free of nicotine.

After the regeneration of column 3 has been completed and the regeneration solution remaining in column 3 has been released through valve 28, valve 19 is closed and column 3 is flushed by means of valve 18 while valves 28, 27 and 26 are closed. The wash water remaining in column 3 is then also released through valve 28.

In the customary manner (not illustrated) care is taken that the regenerating solution and the water used for flushing the column do not mix.

When operating according to schedule 2, valves 1, 2, 8, 5, 11, 12 and 14 are open and valves 7, 3, 9, 4, 10, 6 and 13 are closed. In this case liquid for the nicotine test is withdrawn at valve 16.

For regenerating column 1, valves 19, 20 and 21 are open and valves 22, 24, 23, 25, 26, 27 and 28 are closed. In this case after closing of valve 19, column 1 is emptied through valve 26 and is flushed by opening valve 18 while

valves 26, 27 and 28 are closed. The surplus water is then again withdrawn through valve 26.

When operating according to schedule 3, valves 1, 7, 13, 10, 8, 3 and 9 are open, and valves 2, 4, 5, 6, 11, 12 and 14 are closed. Liquid for the nicotine test is withdrawn at valve 17.

For regenerating column 2, valves 19, 20 and 23 are open and valves 20, 21, 24, 25, 26, 27 and 28 are closed. Column 2 is emptied through valve 27 after valve 19 has been closed, and is then flushed with water by opening valve 18 while valves 26, 27 and 28 are closed. Surplus water is removed through valve 27.

It has been found, upon regenerating exchangers, that only part of the nicotine is exchanged while another considerable part is absorptively attached. Due to this partly absorptive union it is somewhat difficult to quantitatively regenerate the exchanger columns. Satisfactory regeneration can, however, be achieved by using a 7.5% solution of alcoholic hydrochloric acid at raised temperatures of about 40 to 50 degrees centigrade. In consideration of the life span of the exchanger, temperatures in excess of 50 degrees should, if possible, be avoided.

It is advantageous to use the hydrochloric acid for regeneration in a cycle by dividing the total amount into about three to four equal parts.

At the beginning the hydrochloric acid passing through a spent ion exchanger takes up large quantities of nicotine. After a short time, the concentration of nicotine in the regenerating liquid drops considerably and then slowly diminishes further towards the zero value.

In order to save recovery and distillation costs, only the first third or quarter of the regenerating liquid, containing the major portion of the nicotine, is reactivated. The following portions, containing only small amounts of nicotine are used without reactivation for the regeneration of successive spent ion exchanger, and finally, new, or adjusted reactivated regenerating liquid is again introduced.

The first and most saturated portion of the spent regenerating liquid is preferably reworked by distilling off the alcohol and the hydrochloric acid, whereupon the distillation residue contains all the nicotine as chlorohydrate, and also any other ingredients removed from the tobacco. This residue is treated in known ways for the recovery of nicotine.

The nicotine-free alcoholic hydrochloric acid obtained through distillation of the regenerating liquid may be reused upon adjustment of its original composition by addition, if necessary, of alcohol and hydrochloric acid.

The possibility of obtaining nicotine concurrently with the de-nicotinization of the tobacco constitutes a further important advantage of the process in accordance with the present invention, since a considerable part of the operating costs of the process of the present invention may be recovered by the sale of nicotine.

The process of the present invention may also be used for the recovery of soluble ingredients from tobacco wastes under simultaneous separation of the nicotine from the other extractives. This is of considerable economic importance and was not possible until the present process permitted the de-nicotinization of tobacco extracts with the retention of all extractives except for the nicotine.

While it is possible to adjust the metal ion content and pH of these extracts from tobacco wastes to their original values by cycling these extracts through the magnesium carbonate column 23, it has proven especially advantageous to use these extracts from tobacco wastes at the pH at which they are obtained from the ion exchanger. In this case the free organic acids originating in the tobacco and liberated from their salts in the ion exchanger, serve to further improve the quality of so treated tobaccos.

The various process steps are performed simultaneously on subsequent batches of tobacco. In the example, described below, one batch of tobacco containing 33% extractives, including 3% nicotine is followed through the

successive steps of the process in the apparatus shown in the drawing. Description of the simultaneously executed processing of other batches of tobacco in different stages of the process of the present invention has been omitted for the sake of clarity.

EXAMPLES

I

100 pounds of tobacco of the above composition are steeped in tank 2 for one hour in 950 pounds of aqueous tobacco extract coming from tank 5.

During this steeping process 12 pounds of tobacco extractives are dissolved in the aqueous-extract solution.

15 After completion of this first one hour steeping process, the wet tobacco is squeezed through the set of rollers 4. The moist tobacco leaving rollers 4 is dumped into tank 5 and the watery-extract solution which remained in tank 2 is pumped through a filter 15 into the zeolite potassium ion exchanger 16.

20 The moist tobacco received in tank 5 consists of 89 pounds containing 21 pounds of extractives 12 pounds of extractives having been extracted during the first steeping process) and 111 pounds of extract solution. Thus 850 pounds of extract solution remain for pumping into the ion exchanger 16.

II

30 The 200 pounds of moist tobacco received from tank 2 are steeped for one hour in tank 5 with 950 pounds of extract solution coming from tank 8.

35 After completion of this second one hour steeping process, 200 pounds of moist tobacco are dumped into tank 8 via the set of rollers 7 and 950 pounds of watery-tobacco extract solution flow into tank 2 to be used in the first one hour steeping process described under I.

40 The 200 pounds of moist tobacco dumped into tank 8 have a composition of 80 pounds tobacco containing 13 pounds of extractives (8 pounds of extractives having been extracted during the second steeping process) and 120 pounds of extract solution.

III

45 The 200 pounds of moist tobacco received from tank 5 are steeped for one hour in tank 8 with 900 pounds of extract solution coming mostly from conduit 18 and to the extent that conduit 18 does not furnish a sufficient quantity, fresh water to make up the 900 pounds is added from faucet 11.

50 After completion of this third one hour steeping process, 150 pounds of moist tobacco are dumped into tank 19 via the set of rollers 10 and 950 pounds of watery-tobacco extract solution flow into tank 5 to be used in the second one hour steeping process described under II.

55 The 150 pounds of moist tobacco dumped into tank 19 have a composition of 67 pounds of insoluble tobacco constituents and 7 pounds of soluble compounds including a small fraction of the nicotine, and 76 pounds of extract solution.

IV

60 The 850 pounds of concentrated extract solution referred to under I are pumped into the ion exchanger 16, are freed of their nicotine content while passing through the ion exchanger, and are led into conduit 17 which 65 branches into conduits 18 and 20.

66 The extract leaving the ion exchanger contains all of the water soluble extractives removed from the tobacco during the three one hour steeping processes, with the exception of the nicotine and some metal ions like magnesium, which were also retained in the ion exchanger.

70 Part of the extract leaving the ion exchanger flows through conduit 17-18 into tank 8 where together with fresh water added from faucet 11 it makes up the 900 pounds of extract solution used in the third steeping process as described under III.

The 74 pounds of tobacco dry substance received in tank 19 from rollers 10 contain only a small fraction of the original nicotine content (about 0.4 pound), and the extractives contained in the 76 pounds of solution accompanying the 74 pounds of dry substance are practically free of nicotine originating from the tobacco extractives dissolved in the third steeping process.

In this third steeping process (in tank 8), 6 pounds of the extractives contained in the original tobacco are dissolved. The total amount of nicotine dissolved in this step weighs about 0.6 pound. This 0.6 pound of nicotine is dissolved in 950 pounds of extract solution and only 76 pounds of this solution, or less than 10% reach tank 19. Consequently the total amount of nicotine reaching tank 19 amounts to less than 0.05 pound. As will be shown below, the 74 pounds of tobacco dry substance are reconstituted with nicotine-free extracts to about 97 pounds. The so reconstituted tobacco contains less than 0.45 pound nicotine in 100 pounds of untreated tobacco. In other words the nicotine content which has been 3% in the untreated tobacco is thus reduced to about 0.45%.

VI

900 pounds of de-nicotinized extract coming from the exchanger 16 are added by way of conduits 17—20 to the 150 pounds of moist tobacco received in tank 19. The de-nicotinized extract solution in tank 19 is recycled through conduit 21, pump 22, magnesium carbonate column 23, and conduit 24 back to tank 19. It is the purpose of this recycling to restore to the de-nicotinized extract solution the metal-ions which have been retained in the ion exchanger 16, in the form of magnesium-ions. The flow of this recycling process is adjusted so as to permit the metal-ions content of the solution to regain the value it had prior to entering the ion exchanger. (For subsequent batches only small amounts of extract have to be added in order to keep tank 19 properly filled.)

VII

It will be understood that while in the present example the process of the invention is described by following one 100 pound batch of tobacco through the various process steps, actually all steps take place simultaneously with successive batches of tobacco. The recycling of the extract solution from tank 8 to tank 5 to tank 2 through the ion exchanger 16 and back to tank 8, with the addition of only sufficient water to make up for the amount of extract solution which is taken out of the cycle through conduit 20, permits a gradual increase in the extract concentration in the solution to about 20-30%. Once this concentration has been obtained, the thus-formed equilibrium is kept constant as long as the process continues. A concentration of 20-30% extracts in the solution is necessary to successfully complete the final step described below. Suitable arrangements have to be made during the treatment of the first few batches upon starting the process, by either adding sufficiently concentrated extract solution obtained in a previous operation, or by putting aside the first few batches of tobacco until the extract solution has been concentrated and later re-introducing these first few batches in small quantities together with fresh tobacco.

VIII

In the final step of the process, de-nicotinized extracts are added to the extract-free tobacco in tank 19, in sufficient quantities to reconstitute a tobacco containing all of its original extractives, except for the nicotine.

The tobacco-concentrated extract suspension from tank 19 is squeezed through rollers 26. These rollers are so adjusted as to permit the 74 pounds of tobacco to retain 100 pounds of extract solution. Upon subsequent drying of this moist tobacco, the water contained in the extract solution is removed at normal temperatures so as to pre-

vent any chemical changes in the extractives which are now retained in the tobacco.

One obtains from 74 pounds of tobacco dry substance and 100 pounds of a nicotine-free 23% solution of tobacco extractives a total of 97 pounds of reconstituted dry tobacco having a content of extractives of about 31%.

It will be understood that each of the elements described above, or two or more together, may also find a useful application in other types of processing of tobacco differing from the types described above.

While the invention has been illustrated and described as embodied in a three step extraction process, it is not intended to be limited to the details shown, since various modifications and structural changes may be made without departing in any way from the spirit of the present invention, i. e. by increasing the number of extracting steps and/or further diminishing the nicotine content of the tobacco.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

- 30 1. A process of extracting nicotine from tobacco, comprising the steps of treating a predetermined quantity of tobacco with a first amount of water equal to between eight and twelve times the weight of said tobacco so as to extract the water soluble components of said tobacco including the nicotine and metal ions, and form an aqueous extract solution thereof; separating a major predetermined portion of said aqueous extract solution from said tobacco; adding to the thus remaining tobacco an amount of water equal to said first amount of water; separating 40 a portion of the thus formed aqueous extract solution equal to said major predetermined portion thereof; repeating said treating and separating steps with fresh water a predetermined number of times; subjecting said separated extract solutions to ion exchange at a pH not higher than 7.0 with an ion exchanger adapted to remove the nicotine from said extract solutions, thereby obtaining de-nicotinized extract solutions; mixing said de-nicotinized extract solutions with said extracted tobacco so as to form a water-tobacco mixture including the extracted 50 water soluble components of the original tobacco except for the nicotine; and drying said water-tobacco mixture so as to obtain a de-nicotinized tobacco containing substantially all of the original water soluble components thereof except for the nicotine and a portion of the metal ions.
- 55 2. A process of extracting nicotine from tobacco, comprising the steps of treating tobacco with water so as to extract the water soluble components of said tobacco including the nicotine and form an aqueous extract solution thereof; separating said aqueous extract solution containing said nicotine from the thus extracted tobacco; subjecting the thus separated extract solution to ion exchange with an ion exchanger adapted to remove the nicotine from said extract solution, thereby de-nicotinizing and simultaneously removing metal ions from said extract solution and forming a de-nicotinized extract solution having metal ions removed therefrom; replacing said removed metal ions in said de-nicotinized extract solution so as to form a regenerated de-nicotinized extract solution including substantially all of the extracted water soluble components of the original tobacco except for the nicotine; mixing said regenerated de-nicotinized extract solution with said extracted tobacco so as to form a water-tobacco mixture including the extracted water soluble components of the original tobacco except for the 70 75

nicotine; and drying said water-tobacco mixture so as to obtain a de-nicotinized tobacco containing substantially all of the original water soluble components thereof except for the nicotine.

3. A process of extracting nicotine from tobacco, comprising the steps of treating tobacco with water so as to extract the water soluble components of said tobacco including the nicotine and form an aqueous extract solution thereof; separating said aqueous extract solution containing said nicotine from the thus extracted tobacco; subjecting the thus separated extract solution to ion exchange with an ion exchanger adapted to remove the nicotine from said extract solution, thereby de-nicotinizing and simultaneously removing metal ions from said extract solution and forming a de-nicotinized extract solution having metal ions removed therefrom; mixing said de-nicotinized extract solution having said metal ions removed therefrom with said extracted tobacco while adding to the thus formed water-tobacco mixture metal ions of the amount to replace said removed metal ions so as to form a water-tobacco mixture including substantially all of the extracted water soluble components of the original tobacco except for the nicotine; and drying said water-tobacco mixture so as to obtain a de-nicotinized tobacco containing substantially all of the original water soluble components thereof except for the nicotine.

4. A process of extracting nicotine from tobacco, comprising the steps of treating tobacco with a predetermined portion of water so as to extract the water soluble components of said tobacco including the nicotine and form an aqueous extract solution thereof; separating a major predetermined portion of said aqueous extract solution from said tobacco; adding to the thus remaining tobacco a portion of water equal to said predetermined portion of water; separating a portion of the thus formed aqueous extract solution equal to said major predetermined portion thereof; repeating said treating and separating steps a predetermined number of times; subjecting said separated extract solutions to ion exchange with an ion exchanger adapted to remove the nicotine from said extract solutions; thereby de-nicotinizing and simultaneously removing metal ions from said extract solutions and forming de-nicotinized extract solutions having metal ions removed therefrom; replacing said removed metal ions in said de-nicotinized extract solutions so as to form regenerated de-nicotinized extract solutions including substantially all of the extracted water soluble components of the original tobacco except for the nicotine; mixing said regenerated de-nicotinized extract solutions with said extracted tobacco so as to form a water-tobacco mixture including the extracted water soluble components of the original tobacco except for the nicotine; and drying said water-tobacco mixture so as to obtain a de-nicotinized tobacco containing substantially all of the original water soluble components thereof except for the nicotine.

5. A process of extracting nicotine from tobacco, comprising the steps of treating tobacco with a predetermined portion of water so as to extract the water soluble components of said tobacco including the nicotine and form an aqueous extract solution thereof; separating a major predetermined portion of said aqueous extract solution from said tobacco; adding to the thus remaining tobacco a portion of water equal to said predetermined portion of water; separating a portion of the thus formed aqueous extract solution equal to said major predetermined portion thereof; repeating said treating and separating steps a predetermined number of times; subjecting said separated extract solutions to ion exchange with an ion exchanger adapted to remove the nicotine from said extract solutions, thereby de-nicotinizing and simultaneously removing metal ions from said extract solutions and forming de-nicotinized extract solutions having metal ions removed therefrom; mixing said de-nicotinized extract solutions having said metal ions removed therefrom with said extracted tobacco while adding to the thus formed water-

tobacco mixture metal ions of the amount to replace said removed metal ions so as to form a water-tobacco mixture including substantially all of extracted water soluble components of the original tobacco except for the nicotine; and drying said water-tobacco mixture so as to obtain a de-nicotinized tobacco containing substantially all of the original water soluble components thereof except for the nicotine.

6. A process of extracting nicotine from tobacco, comprising the steps of treating a first batch of tobacco with a predetermined amount of water so as to extract the water soluble components of said tobacco including the nicotine and metal ions, and form an aqueous extract solution thereof; separating said aqueous extract solution from said first batch of tobacco; treating a predetermined number of additional batches of tobacco with said separated aqueous extract solution, separating the formed aqueous extract solution from each additional treated batch of tobacco before treating the next batch of tobacco therewith; subjecting the extract solution separated from the last batch of treated tobacco to ion exchange at a pH not higher than 7.0 with an ion exchanger adapted to remove the nicotine from said extract solution, thereby obtaining a de-nicotinized extract solution; mixing an amount of said de-nicotinized extract solution with a batch of extracted tobacco in an amount such that the thus formed water-tobacco mixture contains substantially all of the extracted water soluble components of the original batch of tobacco in the amount originally contained therein except for the nicotine; and drying said water-tobacco mixture so as to obtain a substantially de-nicotinized tobacco containing substantially all of the original water soluble components thereof except for the nicotine and a portion of the metal ions.

7. A process of extracting nicotine from tobacco, comprising the steps of treating a predetermined amount of tobacco with a predetermined amount of water so as to extract the water soluble components of said tobacco including the nicotine and metal ions, and form an aqueous extract solution thereof, the treating being continued at a temperature below 50° C. until the concentration of extractives in the solution reaches an equilibrium value; separating said aqueous extract solution containing said nicotine from the thus extracted tobacco; subjecting the thus separated extract solution to ion exchange at a pH not higher than 7.0 with an ion exchanger adapted to remove the nicotine from said extract solution, thereby obtaining a de-nicotinized extract solution; mixing a predetermined amount of the extracted tobacco with an equal amount of said de-nicotinized extract solution so that the formed mixture contains substantially all of the extracted water soluble components of the original tobacco in the amount originally contained therein except for the nicotine; and drying said water-tobacco mixture so as to obtain a substantially de-nicotinized tobacco containing substantially all of the original water soluble components thereof except for the nicotine and a portion of the metal ions.

8. A process of extracting nicotine from tobacco, comprising the steps of treating several batches of tobacco each with several predetermined portions of water in countercurrent, equal predetermined amounts of the formed extract solutions being separated from each treated batch of tobacco before the next batch of tobacco is treated with the separated equal portion of said extract solution, the formed extract solutions containing the water soluble components of said tobacco including the nicotine and metal ions; continuing the countercurrent treatment by recycling the extract solution from the last batch of tobacco to be treated to the first batch of tobacco until an equilibrium between the concentration of extractives in the solution and the tobacco is attained; subjecting said formed extract solution to ion exchange at a pH not higher than 7.0 with an ion exchanger adapted to remove the nicotine from said extract

solution, thereby obtaining a denicotinized extract solution; mixing a predetermined amount of the extracted tobacco with an equal amount of said denicotinized extract solution so that the formed mixture contains substantially all of the extracted water soluble components of the original tobacco in the amount originally contained therein except for the nicotine; and drying said water-tobacco mixture so as to obtain a substantially denicotinized tobacco containing substantially all of the original water soluble components thereof except for the nicotine and a portion of the metal ions.

9. A process according to claim 8 in which said portions of water are between 8-12 times the weight of said batches of tobacco.

10. A process according to claim 8 in which said portions of water are about 10 times the weight of said batches of tobacco and wherein about 90% of the formed extract solution is separated from each treated batch of tobacco before treatment of the next batch of tobacco therewith.

11. A process of extracting nicotine from tobacco, comprising the steps of treating several batches of tobacco each with several predetermined portions of water in countercurrent, equal predetermined amounts of the formed extract solutions being separated from each treated batch of tobacco before the next batch of tobacco is treated with the separated equal portion of said extract solution, the formed extract solutions containing the water soluble components of said tobacco including the nicotine; continuing the countercurrent treatment by recycling the extract solution from the last batch of tobacco to be treated to the first batch of tobacco until an equilibrium between the concentration of extractives in the solution and the tobacco is attained; subjecting said formed extract solution to ion exchange with an ion exchanger adapted to remove the nicotine from said extract solution, thereby de-nicotinizing and simultaneously removing metal ions from said extract solution and forming a de-nicotinized extract solution having metal ions removed therefrom; replacing said removed metal ions in said de-nicotinized extract solution so as to form a regenerated de-nicotinized extract solution including substantially all of the extracted water soluble components of the original tobacco except for the nicotine; mixing a predetermined amount of the extracted tobacco with an equal amount of said regenerated de-nicotinized extract solution so that the formed mixture contains substantially all of the extracted water soluble components of the original tobacco in the amount originally contained therein except for the nicotine; and drying said water-tobacco mixture so as to obtain a substantially de-nicotinized tobacco containing substantially all of the original water soluble components thereof except for the nicotine.

12. A process according to claim 11 in which said removed metal ions are replaced during the mixing of said extracted tobacco with said de-nicotinized extract solution.

13. A process of extracting nicotine from tobacco, comprising the steps of treating several batches of tobacco each with several predetermined portions of water in countercurrent, equal predetermined amounts of the formed extract solutions being separated from each treated batch of tobacco before the next batch of tobacco is treated with the separated equal portion of said extract solution, the formed extract solutions containing the water soluble components of said tobacco including the nicotine and metal ions; continuing the countercurrent treatment by subjecting the extract solution from the last batch of tobacco to be treated to ion exchange with an ion exchanger adapted to remove the nicotine from said extract solution and recycling said de-nicotinized extract solution to the first batch of tobacco until an equilibrium between the concentration of extractives in the solution and the tobacco is attained; subjecting said formed

extract solution to ion exchange at a pH not higher than 7.0 with an ion exchanger adapted to remove the nicotine from said extract solution, thereby obtaining a de-nicotinized extract solution; mixing a predetermined amount of the extracted tobacco with an equal amount of said de-nicotinized extract solution so that the formed mixture contains substantially all of the extracted water soluble components of the original tobacco in the amount originally contained therein except for the nicotine; and drying said water-tobacco mixture so as to obtain a substantially de-nicotinized tobacco containing substantially all of the original water soluble components thereof except for the nicotine and a portion of the metal ions.

14. A process of extracting nicotine from tobacco, comprising the steps of treating several batches of tobacco each with several predetermined portions of water in countercurrent, equal predetermined amounts of the formed extract solutions being separated from each treated batch of tobacco before the next batch of tobacco is treated with the separated equal portion of said extract solution, the formed extract solutions containing the water soluble components of said tobacco including the nicotine; continuing the countercurrent treatment by recycling the extract solution from the last batch of tobacco to be treated to the first batch of tobacco until an equilibrium between the concentration of extractives in the solution and the tobacco is attained; subjecting said formed extract solution to ion exchange with an ion exchanger adapted to remove the nicotine from said extract solution, thereby obtaining a de-nicotinized extract solution; replacing in a predetermined amount of said concentrated de-nicotinized extract solution the metal ions removed during de-nicotinization of that extract solution, in an amount such that the concentration is in conformity to the concentration of metal ions present in the untreated tobacco; mixing said concentrated de-nicotinized, metal ions-containing extract solution with an equal amount of extracted tobacco so that the formed mixture contains substantially all of the extracted water soluble components of the original tobacco in the amount originally contained therein except for the nicotine; and drying said water-tobacco mixture so as to obtain a substantially de-nicotinized tobacco containing substantially all of the original water soluble components thereof except for the nicotine.

15. A process of extracting nicotine from tobacco, comprising the steps of treating several batches of tobacco each with several predetermined portions of water in countercurrent, equal predetermined amounts of the formed extract solutions being separated from each treated batch of tobacco before the next batch of tobacco is treated with the separated equal portion of said extract solution, the formed extract solutions containing the water soluble components of said tobacco including the nicotine; continuing the countercurrent treatment by recycling the extract solution from the last batch of tobacco to be treated to the first batch of tobacco until an equilibrium between the concentration of extractives in the solution and the tobacco is attained; subjecting said formed extract solution to ion exchange with an ion exchanger adapted to remove the nicotine from said extract solution, thereby obtaining a de-nicotinized extract solution; replacing in a predetermined amount of said concentrated de-nicotinized extract solution the metal ions removed during de-nicotinization of that extract solution, in such amount as to obtain in said predetermined amount of said concentrated de-nicotinized extract solution a pH value substantially equal to the pH value of said formed extract solution prior to its being subjected to ion exchange; mixing said concentrated de-nicotinized, metal ions-containing extract solution with an equal amount of extracted tobacco so that the formed mixture contains substantially all of the extracted water soluble components of the original tobacco in the amount originally contained therein except for the nicotine; and

drying said water-tobacco mixture so as to obtain a substantially de-nicotinized tobacco containing substantially all of the original water soluble components thereof except for the nicotine.

16. A process of extracting nicotine from tobacco, comprising the steps of treating several batches of tobacco each with several predetermined portions of water in countercurrent, equal predetermined amounts of the formed extract solutions being separated from each treated batch of tobacco before the next batch of tobacco is treated with the separated equal portion of said extract solution, the formed extract solutions containing the water soluble components of said tobacco including the nicotine; continuing the countercurrent treatment by recycling the extract solution from the last batch of tobacco to be treated to the first batch of tobacco until an equilibrium between the concentration of extractives in the solution and the tobacco is attained; subjecting said formed extract solution to ion exchange with an ion exchanger adapted to remove the nicotine from said extract solution, thereby obtaining a de-nicotinized extract solution; replacing in a predetermined amount of said concentrated de-nicotinized extract solution the metal ions removed during de-nicotinization of that extract solution, in such amount as to obtain in said predetermined amount of said concentrated de-nicotinized extract solution a pH value between 4.0 and 5.5; mixing said concentrated de-nicotinized, metal ions-containing extract solution with an equal amount of extracted tobacco so that the formed mixture contains substantially all of the extracted water soluble components of the original tobacco in the amount originally contained therein except for the nicotine; and drying said water-tobacco mixture so as to obtain a substantially de-nicotinized tobacco containing substantially all of the original water soluble components thereof except for the nicotine.

17. A process according to claim 16 in which the adjustment of the pH value in said concentrated de-nicotinized extract solution is achieved by cycling said concentrated de-nicotinized solution through a mass of magnesium carbonate until the desired pH value is obtained.

18. A process according to claim 7 in which additional water-soluble ingredients customarily added to tobacco are added to said water-tobacco mixture formed by mixing said de-nicotinized extract solution with said extracted tobacco.

19. A process according to claim 7 in which to said water-tobacco mixture formed by mixing said de-nicotinized extract solution with said extracted tobacco an additional solution containing substantially nicotine-free water soluble tobacco extracts is added.

20. A process according to claim 19 in which said additional de-nicotinized tobacco extract solution is obtained by extracting tobacco waste with water and de-nicotinizing the formed aqueous extract by means of an ion exchanger adapted to remove nicotine from the solution.
